CLAIM

The ornamental design for a seat, as shown and described.

DESCRIPTION

FIG. 1 is a front perspective view of a seat showing my design,

FIG. 2 is a left-side elevational view,

FIG. 3 is a rear elevational view; and

FIG. 4 is a top plan view thereof.

FIG. 5 is a front perspective view of a seat showing a second embodiment of my design,

FIG. 6 is a left-side elevational view,

FIG. 7 is a rear elevational view, and

FIG. 8 is a top plan view thereof.

The pedestal depicted by means of broken lines in FIGS. 1 and 5 has been shown for illustrative purposes only.

FIG. 1
